GEAR DRIVE FOR COMBINED WASHER AND
CENTRIFUGAL DRIERPeter Eduard Geidhof, Syracuse, N. Y., assignor
to Easy Washing Machine Corporation, Syracuse, N. Y., a corporation of Delaware

Application September 30, 1935, Serial No. 42,779

5 Claims. (Cl. 74—81)

My invention relates to washing machines and, more particularly, to a novel driving mechanism for both the agitator and the centrifugal drier of a washing machine.

5 An object of my invention is to provide a novel drive mechanism for a washing machine which is economical to build and by which the agitator of the washing machine may be oscillated and the centrifugal drier may be rotated from the 10 same source of power.

A further object of my invention is to provide a drive mechanism for the agitator and the centrifugal drier of a combined washing and drying machine in which the segment gear for oscillating the agitator is connected to the driving mechanism through an eccentric disk and pitman, whereby the pitman may be rigidly supported and the provision of independent clutches for both the washer and drier, whereby either 20 the washer or drier may be disconnected from the driving mechanism.

Other objects and advantages of my invention will be more apparent from the following description when taken in connection with the 25 accompanying drawings, in which:

Figure 1 is a view, partly in section, showing the agitator and centrifugal drier mounted in operative position and showing the driving mechanism therefor.

30 Figure 2 is a view taken on the line 2—2 of Figure 1.

Figure 3 is a view taken on the line 3—3 of Figure 2.

35 Figure 4 is a view taken on the line 4—4 of Figure 5.

Figure 5 is a view taken on the line 5—5 of Figure 2.

40 Figure 6 is a view taken on the line 6—6 of Figure 5.

Figure 7 is a view taken on the line 7—7 of Figure 1.

45 Figure 8 is a view taken on the line 8—8 of Figure 7.

Figure 9 is a view taken on the line 9—9 of Figure 7.

Figure 10 is a view taken on the line 10—10 of Figure 2.

The driving mechanism constituting part of 50 my invention is adapted to be mounted in a housing or casing 11 having an upper portion 12 and lower portion 13, which are secured together by suitable studs. The casing 11 is suspended beneath vats 14 and 16 constituting, respectively, the washer vat and the drier vat. A

suitable top support 15 extending around the top of both vats for receiving covers 20 for the vats is provided. The vats are supported by legs 17, preferably three in number, only two of which are partly shown. An apron 18 is secured to the bottom of the vats and extends downwardly over and partially encloses the casing 11. An agitator 19 of any suitable design is mounted in the washer vat 14 and is adapted to be oscillated by means of a shaft 21 to which it is secured. The 10 shaft 21 projects downwardly below the bottom of the vat and into the casing 11 where it is journaled in a boss and provided with a ball thrust bearing 25. A sleeve 22 surrounding the agitator shaft serves to support the shaft and, when suitable packing is used, to prevent leakage of cleansing fluid around the shaft. The bottom of the sleeve is threaded into a bracket 23 which may be formed integral with the top half of the casing.

A clothes drier, generally indicated by the numeral 24, is mounted in the drier vat 16 and is adapted to be rotated by a shaft 26 to which it is secured. A sleeve 27 surrounds the shaft 26 so as to support the shaft and is provided with suitable packing to prevent leakage of fluid out of the drier vat. The bottom of the sleeve is threaded into a bracket 28 which may be formed integral with the casing. The shaft 26 projects downwardly into the casing and is journaled in a boss in the bottom thereof and is provided with a ball thrust bearing 30.

The mechanism for driving the agitator shaft 21 and the drier shaft 26 comprises, as shown 35 more clearly in Figure 2, a motor 29 secured in any suitable manner to the casing. The motor shaft 31 projects outwardly from the motor casing and is coupled to a shaft 32 by means of a coupling of any suitable type, indicated by the numeral 33. The shaft 32 has mounted thereon a pulley 34 which by means of a belt 36 drives a pulley 37. The pulley 37 drives a pump 38, not necessary to describe in detail. The pump is secured to the casing by a bracket 39 and is 40 used to pump cleansing fluid from the washer vat or to pump the cleansing fluid extracted from the clothes from the drier vat back into the washer vat or into an external vessel. The shaft 32 projects into the casing 11 and has a suitable bearing support 41. The shaft 32 also has a bearing 43 at the opposite end and an intermediate bearing 44. Mounted on the shaft 32 or preferably formed integral therewith, is a worm gear 46 which drives a worm wheel 47. Also 45

50 55

mounted on the shaft 32 is a spiral gear 48 which drives a drier gear 49 fixed to shaft 26.

The worm wheel 47, as shown more clearly in Figure 1, is mounted loosely on a shaft 51 which 5 is rigidly fitted into bosses 52 and 53 formed respectively in the bottom and top halves of the casing. The worm wheel 47 has integrally formed on the top face thereof, an eccentric disk 54. A pitman 56 having an enlarged head integral 10 therewith forming an annular strap 55 is fitted over the eccentric disk and is rotatable with respect thereto. The opposite end of the pitman 56 is fixed to a stud 57 pivoted in a segment gear 58. The segment gear is pivoted on a pin 59 projecting upwardly from the bottom wall of the casing 11 and is in mesh with an agitator drive pinion 61 which is mounted loosely on the agitator drive shaft 21. The shaft 21 is provided 15 with a pin 62 extending through the shaft, the projecting ends of which are beveled to form flat surfaces extending upwardly at an acute angle to each other, as indicated in the drawings. The agitator drive pinion 61 has a projecting hub 63 provided with slots 64 adapted to cooperate 20 with the flat surfaces of the pin 62 so that when the slots 64 are in engagement with the ends of the pin, the shaft 21 may be oscillated by means of the segment gear 58.

Means are provided for raising the agitator 30 drive pinion 61 a distance sufficient to disengage the slots 64 from the ends of the pin 62 so that although the gear is rotated by the segment gear and retained in engagement therewith, it does not drive the agitator shaft. As shown more clearly 35 in Figure 8, the gear 61 is raised by means of a bifurcated clutch shifting plate 66, the bifurcated ends of which engage in a groove 67 formed at the top of the gear 61.

A clutch rod 68, extending through an opening in a boss 69 formed in the top of the casing 11, is secured to the end of the clutch shifting plate 66 and is normally urged downward by a spring 71 so as to bring the slots 64 and the ends of pin 62 constituting the clutch elements in engagement. The end of the clutch rod 68 has a longitudinally extending slot 72 for receiving a clutch lever 73 operatively connected to the clutch rod 68 by a pin 74 extending through the end of the clutch rod. The end of the clutch lever 50 is slotted at 76 to receive the pin 74, thus providing a lost motion connection between the clutch lever and the clutch rod. The clutch lever 73 is pinned, as indicated at 77 in Figure 7, to a clutch control rod 78 which is preferably formed in two parts, as illustrated in the drawings, to facilitate 55 assembly. The clutch control rod is journaled in the bracket 23 and the outer end is secured to an eccentric arm 79 which is pivoted to a link 81. The link 81 is pivoted to an eccentric arm 82 and the eccentric arm 82 is rigidly secured at 83 to a rod 84 operable by means of a suitable handle 86.

A bar 87 secured at 88 to the bracket 23 has an adjustable eye-bolt 89 secured therein for receiving one end of a spring 91 which has its opposite end secured to the other end 92 of the clutch control rod 78. The end of the clutch control rod is bent, as indicated at 93 to form a crank arm. By means of spring 91, the clutch control rod may be retained in positions such 70 that the clutch 62, 64 is engaged or disengaged, downward movement of the clutch rod 68 being limited by engagement of the clutch elements and upward movement being limited by the 75 clutch lever 73 striking the bracket 23.

Operation of the centrifugal drier is controlled by a separate clutch mounted on the drier shaft 26, shown more clearly in Figure 5. The gear 49, driven by the spiral gear 48, is rigidly mounted on the shaft 26 and has integrally formed therewith a hub 94, the end of which is enlarged, as indicated at 96, and constitutes one clutch element 97 of a drier clutch. A second clutch element 98 is keyed to the shaft by a Woodruff key 99, enabling the clutch element 98 to be non-rotatably secured thereto but slideable along the shaft. The clutch element 98 is normally urged downwardly by means of a pressure spring 101 which surrounds an enlarged hub of the clutch element 98. The upper end of the spring 101 is 10 confined by a clutch spring retaining flange 102. A snap ring 103 holds the clutch spring retaining flange in position, the clutch spring retaining flange being rotatable on a bearing 104. The clutch element 98 is provided with a facing 106 15 of any suitable friction clutch material.

Surrounding the clutch element 97 and concentric therewith is a brake shoe 107 which is movable into and out of engagement with the outer circumference of the clutch surface 106. 20 The brake shoe 107 is provided with bosses 108, more clearly shown in Figure 4, which are slidably received in vertically extending grooves 109 formed in the casing 11. A yoke 111 is in engagement with the under surface of the brake shoe 30 and is pinned to a clutch control rod 112. The clutch control rod 112 is slidably supported in the casing being reciprocable therein by rack teeth 113 which are in engagement with teeth 114 formed on the end of a shaft 116. An eccentric arm 117 is pinned to the shaft 116 and has its other end pivotally secured to a link 118. Pivoted to the other end of the link 118 is an eccentric arm 119. The eccentric arm 119 is rigidly secured, as indicated at 121 to a rod 122. The rod 40 122 has a suitable operating handle 123.

When the machine is in operation, the shaft 32, the worm wheel 47, the segment gear 58, the agitator drive gear 61 and the drier drive gear 49 are in constant operation and the drier and washer may be operated simultaneously or separately by the engagement and disengagement of the aforementioned agitator and drier clutches. When the clutch lever 73 is in the position shown in Figure 8, the clutch elements 62 and 64 are 50 held in engagement by the spring 71 so as to drive the agitator. In this engaged position of the clutch elements, the clutch control rod 78 is retained in position against accidental displacement by the spring 91. When it is desired 55 to stop the agitator, the clutch control rod is manually rotated by means of handle 86 so that the slot 76 is moved with respect to the pin 74. When the clutch control rod has been moved far enough, it engages the end of the slot and pulls the clutch rod upwardly against the tension of the springs 71 and 91. Further upward movement of the clutch lever 73 brings the end 92 into a position above the axis of the control rod so that the spring 91 retains the clutch elements 65 out of engagement, the clutch lever 73 striking the bracket 23 to limit the upward movement thereof. The agitator drive pinion is thus raised high enough to disengage the clutch elements without disengaging the agitator drive pinion 70 from the segment gear.

When the drier clutch is in the position shown in Figure 5, the drier is being rotated through gears 48 and 49. When it is desired to stop rotation of the centrifugal drier, the handle 123 is 75

manipulated so as to rotate the shaft 116 and cause the clutch control rod 112 to move upwardly carrying with it the yoke 111. Upward movement of the yoke 111 brings the brake shoe 5 107 into engagement with the clutch surface and raises the clutch element 98 out of engagement with the clutch element 97 against the pressure of spring 101. The engagement of the brake shoe with the clutch surface 106 causes the centrifugal 10 drier to be quickly stopped.

Of particular importance in the driving mechanism of my invention is that the driving mechanism is in constant operation, the pitman 56 is rigidly supported in the casing, the controls of 15 the drier and washer are entirely independent and the washer may be controlled without disengaging the agitator drive gear 61 from the segment gear 58. It will be apparent that I have provided a novel common driving mechanism for 20 an agitator and a centrifugal drier and that various changes and modifications may be made in the form and relation of parts of the driving mechanism without departing from the spirit of the appended claims.

25 I claim:

1. In a driving mechanism for a washer and a drier, a drive shaft, a worm gear and a second gear mounted on said shaft, a drier shaft, a drier gear in mesh with said second gear and loosely 30 mounted on said shaft, means for connecting and disconnecting said drier gear to and from the drier shaft, a worm wheel in mesh with said worm gear, an eccentric disk driven by said worm wheel, a washer shaft unconcentric with respect 35 to said drier shaft and having a washer drive gear loosely mounted thereon, means for driving said washer drive gear from said eccentric disk, and means for connecting and disconnecting said washer drive gear to and from said washer drive 40 shaft.

2. In a driving mechanism for a washer and a centrifugal drier, a drive shaft, a worm gear and a second gear mounted on said shaft, a drier shaft, a drier gear in mesh with said second gear and loosely 45 mounted on said shaft, means for connecting and disconnecting said drier gear to and from said drier shaft, a worm wheel in mesh with said worm gear, an eccentric disk driven by said worm gear, a washer shaft unconcentric with 50 respect to said drier shaft and having a washer drive gear loosely mounted thereon, means for driving said washer drive gear from said eccentric disk comprising a segment gear constantly in mesh with said washer drive gear, pins on said 55 washer drive shaft and notches on said washer drive gear, and manually operated means for disengaging the notches from the pins while retaining the segment gear in mesh with the washer drive gear.

60 3. In a driving mechanism for an oscillatable washing element and a centrifugal drier, a gear

casing, a washer shaft projecting from said casing and a drier shaft projecting from said casing, said two shafts being unconcentric, a motor driven drive shaft projecting into said casing, a worm and a second gear in said casing mounted 5 on said drive shaft, a drier gear in said casing loosely mounted on said drier shaft and in mesh with said second gear, a clutch in said casing for connecting and disconnecting said drier gear to and from said drier shaft, a worm wheel in mesh 10 with said worm and having a shaft supported at both ends in said casing upon which said worm wheel is loosely mounted, an eccentric disk driven by said worm wheel, a washer gear in said casing loosely mounted on said washer shaft, means for driving said washer gear from said eccentric disk comprising a segment gear constantly in mesh with said washer gear, pins on said washer shaft and notches on said washer gear, and manually operable means for disengaging the notches from 15 the pins while retaining the segment gear in mesh with the washer drive gear.

4. In a control mechanism for the agitator of a washing machine, an agitator drive shaft having pins extending therefrom, a gear loosely 25 mounted on said shaft and having cooperating slots adapted to engage said pins to connect said gear to said shaft, a constantly driven rack element in mesh with said gear, means for moving said gear to disconnect said gear from said shaft 30 comprising a control element, a spring normally urging said control element in a direction to connect said gear to said shaft, and a hand operated element having a lost motion connection between said control element and said hand operated element, and means comprising a spring 35 for retaining said control element in either of two positions.

5. In a control mechanism for the agitator of a washing machine, an agitator drive shaft having pins extending therefrom, a pinion gear mounted loosely on said shaft and having cooperating slots adapted to engage said pins to connect said pinion gear to said shaft, a constantly driven rack element in mesh with said pinion gear, said rack element being in mesh with said pinion gear both when the slots are in engagement with the pins and when they are out of engagement therewith, means for moving said pinion gear to move said slots out of engagement 40 with said pins to disconnect said pinion gear from said shaft comprising a control element, a spring normally urging said control element in a direction to connect said pinion gear to said shaft, a hand operated element having a lost motion connection between said control element and said hand operated element, and means comprising a spring 45 for retaining said control element in either of two positions.

60 PETER EDUARD GELDHOF.
